Specification of Letters Patent.

Patented Apr. 6, 1920.

Application filed September 16, 1918. Serial No. 254,280.

To all whom it may concern:

Be it known that I, ARTHUR COBB, a citizen of the United States, residing at Cleveland, in the county of Cuyahoga and State 5 of Ohio, have invented a certain new and useful Improvement in Bookbinding, of which the following is a full, clear, and exact description.

This invention is a durable, sanitary, 10 easily applied book cover, which is of perhaps greatest practical value for rebinding books whose original covers have become unserviceable for one reason or another; although, obviously, the cover may be applied 15 in the first instance to the coverless, sewed-together sheets of printed paper constituting the book or insert.

The cover constituting this invention is made of sheet metal,—the various parts of 20 which are constructed and combined substantially as shown in the drawings, and hereinafter described and pointed out definitely in the appended claims.

In the drawings, Figure 1 is a side elevation of the book cover, Fig. 2 is an inside view of the back part of one of the cover sides and book insert to which the cover is applied, when the cover is swung open; Fig. 3 is a sectional end view (slightly enlarged) 25 in the plane of line 3—3 of Fig. 1; Fig. 4 is an enlarged sectional view of the back of the book and cover in the plane of line 4—4 on Fig. 1. Fig. 5 is a similar section in the plane of line 5—5 of Fig. 1. Fig. 6 is a similar section going about half way through the book in the plane of line 6—6 of Fig. 1, 30 and Fig. 7 is a detached view of one of the hinge lugs.

The cover as shown is made of various 40 parts formed from thin sheet metal which of course may be enameled or otherwise protectingly coated. The cover includes in its entirety a back 10, two sides 20—20, at least four hinge lugs 35, two associated with each 45 side, and two hinge pintle wires 30, one associated with each side.

The back 10 is curved so as to have substantially the shape which the backs of ordinary book covers have. The side edges of 50 the back are bent forward forming side flanges 12 between which the sewed-together back of the paper book or insert B projects when the cover has been applied to said book. Preferably these side flanges are bent

so that if they were prolonged they would 55 intersect at about the middle of the book. If bent into this position they permit the sides to swing farther back, as shown by dotted lines in Fig. 4, than they could be swung if said flanges were only bent into 60 parallel positions.

At suitable points, preferably about one and one half inches from the top and bottom of the back two tongues are formed integral with each flange. Each of these tongues is 65 bent so as to form a hinge barrel 13; and of course the two hinge barrels on the same side must be in alinement. When the flanges 12 are bent into the angular relation shown, these tongues are preferably bent outward 70 at their line of juncture with the flange, as shown in Fig. 4, and are then curved inward to form the hinge barrels substantially as shown.

Each of the cover sides 20 is likewise 75 formed of thin sheet metal. A sunken panel 21 is pressed centrally into the cover side; and the four edges or flaps 22, 23, 24, 25, of each cover are bent inwardly so as to form the double thick marginal edge around said 80 cover panel. The extreme edges of the bent over flaps of each cover side engage the edges of the inwardly pressed panel, and the corners of the flaps are mitered to fit one another, so that the inner surfaces of said 85 flaps lie in substantially the same plane as the inner surface of the panel. A sheet of paper or cloth may be glued to this inner surface thereby concealing the joints, and covering the slot 28 in the rear flap. 85

In the U-shaped or looped rear edge 25^a of each cover side two slots 26 are cut out. Part of the metal cut out to form these slots remains attached at one edge and is bent across the space between the cover side and 95 the turned over margin thereof, and thereby forms an inner wall 27 for said slot. A slot 28 is also cut out of the turned over rear flap of each cover as shown in Fig. 2.

In the chamber or space between the cover 100 side and the rear turned over flap 25 thereof, a movable hinge pintle wire 30 is placed. This is bent into substantially the shape shown so that one end 31 is bent back upon itself toward the opposite end 32 and into 105 alinement therewith. At some point midway between the ends of this pintle wire and at such a point that it is accessible through

the slot 28 this wire is formed with a kink 33, the purpose of which will be presently explained.

35 represents hinge lugs. There are at 5 least four of these, two associated with each cover, and with each side of the back. Each of these hinge lugs has a prong, preferably in the form of a flat blade 36 which is to be forced through a considerable number of the 10 leaves of the book insert from the outside thereof toward the middle but close to the rear edge of said book insert. Of course, the holes in the book to receive these prongs may be formed in the book by some suitable 15 tool. Each of these hinge lugs is formed with a hinge barrel 37.

To assemble these parts the hinge lugs are first attached to the book insert at the proper places and in the manner stated. 20 That is to say, the prongs thereof are forced into the book insert near the back edge thereof, and in such position that the hinge barrels of said lugs can coöperate with the hinge eyes on the back in the manner 25 shown. Then the book with these hinge lugs attached to it is placed in the proper relation to the back, that is to say, the back of the book is inserted between the side flanges 12, with the hinge barrels 37 in substantial end contact and in alinement with 30 hinge barrels 13. Then the sides are applied, one by one, by so placing them as shown with respect to the back and the book insert that the two pairs of alined hinge barrels 37 and 13 go into and fit each of the 35 slots 26 in the rear edge of the side.

When the parts are in this position a tool of some sort is passed through the slot 28, and by engaging with the kink 33 of the 40 wire pintle, pushes said pintle endwise, thereby causing the two ends 31, 32, to pass through the alined hinge barrels 13 and 37, thereby hinging together the cover side, hinge lugs and back.

45 When the hinge wire is in the proper position a lug 29 left on the edge of the slot 28 may be made to engage behind the kink 33 and prevent any such movement of the wire as will carry its ends out of the hinge barrel.

This having been done the other side will be applied in the same manner. Any endwise movement of the hinge barrels with respect to each other or to the cover sides is 55 prevented by the ends of the slots 26. Each cover may, however, be swung open or closed about its hinge axis without causing any movement of the parts to which it is hinged,—and, when the back is formed as 60 shown, may be swung back very far without imposing any strain upon itself or the associated parts. The book may be opened flat at any page thereof, because the hinging of the hinge lugs to the back and cover per-

mits the back of the book insert to have substantially the same independent freedom of movement as the backs of books bound in the usual way.

As a detail which is of some practical value, attention is called to the fact that the 70 blades 37 of each hinge barrel may be formed with numerous holes 38 through them. It is intended that the holes shall be filled with glue and that both surfaces of the blade shall be coated with glue before 75 the blades are driven into the holes in said insert. This will effectively aid in keeping the blades in position in which they are driven.

The described construction is obviously 80 very strong and durable. The cost of constructing and applying one of these covers to a book insert will, it is thought, be less than the cost of rebinding the book. Additionally the cover is capable of being used 85 over again with different book inserts; and may be applied by a library assistant in his leisure time. If the metal be properly enameled the cover can be kept in a clean and sanitary condition.

Having described my invention, I claim:—

1. A book cover, comprising, in combination, a metal back plate, a set of metal hinge lugs and a cover side,—all of which are hinged on the same axis to one side edge of 95 the back plate and are free to swing independently about that axis; another set of metal hinge lugs and another cover side,—all of which are hinged to the same axis to the other side edge of the back plate and are 100 free to swing independently about that axis, all of said hinge lugs being formed at their free ends with means for connecting them to a book insert to thereby secure the book 105 insert within the cover.

2. A metal book cover comprising in combination a metal back having integral hinge barrels at its edges, hinge lugs each having a prong capable of being inserted in the book to be covered and having also a hinge 110 barrel adapted to be alined with a hinge barrel on the back, and two sides each pivotally connected with hinge barrels of the back and of the hinge lugs.

3. The combination of a sewed together 115 paper book, of a metal back having forwardly bent side flanges, hinge lugs having prongs which are inserted into the book from opposite sides thereof and near its back, two sides, and means pivotally connecting said sides, hinge lugs and side flanges of the back.

4. A book cover comprising in combination a back having turned over flanges on its vertical edges, and hinge barrels formed 125 integrally with said flanges, hinge lugs each having a prong adapted to be inserted in a book near its back and having also a hinge

barrel, and two sides, and a pintle wire associated with each side pivoting it to the hinge barrels of the hinge lugs and the back.

5. A metal book cover comprising in combination a back having forwardly bent side flanges, and hinge barrels which project forward from said flanges, metal hinge lugs each having a prong adapted to be inserted into the book to be bound, and having also a hinge barrel, two cover sides, each having in its back edge a recess fitted to receive two aligned hinge barrels, one on the back and one on a hinge lug, and means pivotally connecting the back edge of each cover with the associated hinge barrels of the back and associated hinge lugs.

6. A metal book cover comprising in combination a back having forwardly bent side flanges and hinge barrels integral with said side flanges, hinge lugs each having a prong adapted to be inserted into the book to be covered, and each having a hinge barrel adapted to be aligned with and to be in substantial contact with a hinge barrel on the back, and two metal cover sides each comprising a metal plate, the rear edge of which is folded over on a flap to form a double thick rear margin and a U-shaped rear edge,—there being slots in the U-shaped rear edge of said plate each adapted to receive a hinge barrel on a hinge lug and a hinge barrel on the back, and a pintle wire in the space formed between the cover and its folded over rear flap having its ends alined and pointing in the same direction, said wire being movable with respect to the cover so that the two ends thereof may be threaded through the hinge barrels of the back and hinge lug.

40 7. A metal book cover comprising in combination a back having forwardly bent side flanges and hinge barrels integral with said side flanges, hinge lugs each having a prong adapted to be inserted into the book to be covered, and each having a hinge barrel adapted to be aligned with and to be in substantial contact with a hinge barrel on the back, and two metal cover sides each comprising a metal plate, the rear edge of which is folded over as a flap to form a double thick rear margin and a U-shaped rear edge, there being slots in the U-shaped rear edge of said plate each adapted to receive a hinge barrel on a hinge lug and a hinge barrel on the back, and a pintle wire in the space formed between the cover and its folded over rear flap having its ends alined and pointing in the same direction, said wire being movable with respect to the cover so

that the two ends thereof may be threaded 60 through the hinge barrels of the back and hinge lugs,—and the folded over rear flap of the cover side having a slot for the insertion of a tool to so move said pintle wire.

8. A metal book cover comprising in combination a back having forwardly bent side flanges and hinge barrels integral with said side flanges, hinge lugs each having a prong adapted to be inserted into the book to be covered, and each having a hinge barrel 65 adapted to be aligned with and to be in substantial contact with a hinge barrel on the back, and two metal cover sides each comprising a metal plate, the rear edge of which is folded over on a flap to form a double 70 thick rear margin and a U-shaped rear edge,—there being slots in the U-shaped rear edge of said plate each adapted to receive a hinge barrel on a hinge lug and a hinge barrel on the back, and a pintle wire 75 in the space formed between the cover and its folded over rear flap having its ends alined and pointing in the same direction, said wire being movable with respect to the cover so that the two ends thereof may be threaded through the hinge barrels of the back and hinge lugs,—and the folded over rear flap of the cover side having a slot for the insertion of a tool to so move said pintle wire, and means carried by 80 said cover side for engaging said pintle wire to prevent the accidental endwise movement thereof.

9. A metal book cover comprising, in combination, a back having forwardly bent side 95 flanges and hinge barrels integral with said side flanges, hinge lugs each having a prong adapted to be inserted into the book to be covered and each having a hinge barrel adapted to be aligned with and to be in substantial contact with a hinge barrel on the back, and two metal cover sides each formed 100 of a metal plate having a single thick central panel and having flaps on its four sides which are folded inwardly into parallel relation with the side and into contact with the margin of the panel and having fitted mortised corners,—the U-shaped rear edge of said cover plate having slots each adapted to receive the hinge barrel of a hinge lug 105 and a hinge barrel of the back, and pintle wire lying within the U-shaped rear edge of said cover plate and passing through the alined hinge barrels.

In testimony whereof I hereunto affix my 115 signature.

ARTHUR COBB.
